SPEED SHIFT HOUSING FOR A BICYCLE HAVING DUAL CROSS BARS

Hans-Jurgen Lannoch, Hochstetten, Germany, assignor
to Fichtel & Sachs AG, Schweinfurt, Germany

Filed Feb. 19, 1971, Ser. No. 117,220

Claims priority, application Germany Sept. 16, 1970

Term of patent 14 years

Int. Cl. D12—16

U.S. Cl. D90—1

FIG.1

FIG.2

FIG.3

FIG.4

FIG. 1 is a side elevational view of a speed shift housing for a bicycle having dual cross bars embodying my new design;

FIG. 2 is a top plan view thereof;

FIG. 3 is a rear-elevational view thereof; and
FIG. 4 is a front elevational view thereof.

The cross bars of the bicycle are fragmentarily shown in chain-dotted lines for illustrative purposes only.

I claim:

The ornamental design for a speed shift housing for a bicycle having dual cross bars, as shown and described.
